US00D746989S

(12) **United States Design Patent**
Goldberg

(10) **Patent No.:** **US D746,989 S**
(45) **Date of Patent:** **** Jan. 5, 2016**

(54) **IMPLANT**

(71) Applicant: **CATALYST ORTHOPAEDICS LLC**,
Naples, FL (US)

(72) Inventor: **Steven S. Goldberg**, Naples, FL (US)

(73) Assignee: **CATALYST ORTHOPAEDICS LLC**,
Naples, FL (US)

(**) Term: **15 Years**

(21) Appl. No.: **29/531,101**

(22) Filed: **Jun. 23, 2015**

Related U.S. Application Data

(63) Continuation of application No. 29/471,474, filed on Oct. 31, 2013, now Pat. No. Des. 735,338, which is a continuation of application No. 14/069,154, filed on Oct. 31, 2013.

(57) **CLAIM**

The ornamental design for an implant, as shown and described.

DESCRIPTION

FIG. 1 is a front left perspective view of an implant; FIG. 2 is a back left perspective view of the implant; FIG. 3 is a back view of the implant; FIG. 4 is a front view of the implant; FIG. 5 is a right view of the implant; FIG. 6 is a left view of the implant; FIG. 7 is a top view of the implant; FIG. 8 is a bottom view of the implant; FIG. 9 is a cross sectional view of a left portion of the implant taken along line 9-9 of FIG. 3; and, FIG. 10 is a cross sectional view of a bottom portion of the implant taken along line 10-10 of FIG. 3. In the drawings, the broken lines depict environmental subject matter only and form no part of the claimed design.

1 Claim, 5 Drawing Sheets
